UNITED STATES PATENT OFFICE.

EDDO V. BATES, OF DRACUT, ASSIGNOR OF ONE-HALF TO THOMAS McNAMARA, OF LOWELL, MASSACHUSETTS.

FEEDING MECHANISM FOR CARDING-MACHINES.

SPECIFICATION forming part of Letters Patent No. 534,418, dated February 19, 1895.

Application filed February 11, 1893. Serial No. 461,898. (No model.)

To all whom it may concern:

Be it known that I, EDDO V. BATES, a citizen of the United States, residing at Dracut, in the county of Middlesex and Commonwealth of Massachusetts, have invented a certain new and useful Improvement in Feeding Mechanism for Carding-Machines, of which the following is a specification.

My invention relates to carding machinery and consists of devices and combinations hereinafter described and claimed, and includes an improved feeding apparatus for feeding slivers positively.

In the accompanying drawings on five sheets, Figure 1 is a perspective view of a carding engine provided with my improvements. Fig. 2, is a plan of the feed aprons, feed-rolls, tumbler, feeding-head or distributing carriage and actuating mechanism with parts of the frame; Fig. 3, a front elevation of the distributing carriage, a part of the frame on which it travels, a sprocket-chain which causes said carriage to traverse, and one of the side-belts; Fig. 4, a plan of what is shown in Fig. 3; Fig. 5, a front elevation of a part of the frame on which the distributing carriage travels at the right of the machine, showing the gearing which drives the sprocket-chain and rotates the shaft by which the distributing rolls of the carriage are operated, showing also in front elevation one of the side-belts; Fig. 6, a plan of the parts shown in Fig. 5, omitting the side-belt; Fig. 7, a rear view of the spur gears shown in Fig. 5, a part of the frame shown in Fig. 5, and the rotary shaft supported therein; Fig. 8, a left-side elevation of the distributing carriage, its actuating gear and one of the feed aprons, showing in section the carriage supporting-rail and the feed-table and the carriage operating shaft and sprocket-chain; Fig. 9, a right-side elevation of the carriage, omitting the stud on which the chain-engaging pin slides and a cross-section of the carriage-actuating shaft; Fig. 10, a horizontal section on the line 10 10 in Fig. 9. Fig. 11 is a central vertical section of the main cylinder, the tumbler, the lumper-roll, feed-rolls, feed-table, one of the feeding-aprons, showing also in elevation a part of the side-shaft through which motion is communicated from the lower doff-

fer-roll and the gears which connect said side-shaft and the feed-rolls; Fig. 12, a plan of a part of the frame, a part of the main cylinder and its shaft, the fast pulley and loose pulley on said shaft and a plan of the mechanism which drives the feed-rolls and the lumper-roll from the shaft of the lower doffer; also a part of said last-named shaft; Fig. 13, a side elevation of the link of the sprocket-chain which carries a pin to engage the slide on the carriage and a vertical section of said slide in the plane of the axis of said pin.

In Figs. 1, 2, 11 and 12, A denotes the frame of a breaker-card; B, the main cylinder; C, the tumbler; D, the workers; D', the stripers; E, the upper and E' the lower doffer; F, the rubbers or rub-rolls, between which the rovings pass from the doffers to the spools G, the latter being rotated by a frictional contact of said spoolers or of the rovings wound around them, with the drums H, these parts being all of the usual construction and operation as used in wool-carding engines.

The sliver-feeding devices hereinafter described are an improvement on the so-called Apperly feed, said Apperly feed being shown and described in United States Letters Patent No. 18,888, granted December 22, 1857, to James Apperly and William Clissold.

The frame a', represented in Fig. 2, supporting apron-rolls i i' (Figs. 2 and 11), on which run narrow feed-aprons I of card-cloth, the feed-rolls N' N², and the side-belts K, are of the usual construction and operation as commonly used in the so-called Apperly feed and are substantially as shown in said patent, except as hereinafter stated. Instead of the floor-delivery shown in said patent, an overhead delivery is now commonly used, as represented in Fig. 1, consisting of a grooved pulley L, journaled in a laterally swinging arm l, and having a positive and uniform motion from a belt l'. The distributing carriage is represented in said patent as caused to traverse by an endless belt, a horizontal pin, rigidly secured to said belt, engaging a vertical slot in said carriage. In practice, the belt is found to slip on its pulleys, and to vary its speed, making unequal intervals between the courses of the drawing on the feed-aprons, and making the rovings of varying diameter

and weight. I drive the carriage M by an end-less chain M', running on the sprocket-wheels m m', the wheel m' being fast on the same shaft m² with the bevel-pinion m³, said pinion 5 m³ being engaged by another bevel-pinion m⁴, fast on the same shaft m⁵ with the spur-gear m⁶, said gear m⁶ being driven by a pinion m⁷, concentric with and turning with the band-pulley m⁸, and said pulley m⁸ being connected 10 by a belt m⁹, with a band-pulley m¹⁰, fast on the shaft of the upper rear feed-roll N³, hereinafter described (see Figs. 2 to 6), one link of the chain M' having a pin m²⁶ which enters a hole m²⁷ in a slide m²⁸, capable of moving vertically on a stud m²⁹, fixed in the top of said carriage. (See Fig. 13.) The shaft m⁵ is by the 15 means above described rotated at a uniform speed.

The guide-frame O is supported by vertical 20 posts o o' on the frame a' and consists of a bottom-rail o² (Figs. 2 to 8), shaped in cross-section like an inverted T and having at its ends stands o³ o⁴, in which is journaled a shaft O' which guides and supports said carriage M 25 and also drives distributing-rolls m¹¹ m¹² hereinafter described.

The shelf o⁵ or rear part of the base of the rail o² supports standards o⁶ o⁷, in which the shafts m¹³ m² of the sprocket-wheels m m' are 30 journaled, and which are secured to said rail o² by bolts o⁸ which pass through said standards and through slots o⁹ in the vertical web o¹⁰ of said rail, said slots permitting the lateral adjustment of the standards when necessary to tighten the chain M' or to adjust the 35 position of the gears on the shaft m² to the gears by which they are engaged. The tension of said chain M' may also be varied by raising or lowering the idle sprocket-wheel 40 m¹⁴ which turns loosely on a horizontal stud o¹¹ rigidly secured to a plate o¹² which, by means of bolts o¹³ passing through a vertical slot o¹⁴ in said plate into a standard o¹⁵ (substantially like the standard o⁶ and supported 45 in like manner therewith), may be held at any desired height.

The carriage M (Figs. 3, 4, 8, 9, 10 and 13) consists of a vertical plate m³⁰ having three 50 backwardly-extending brackets m¹⁵ m¹⁶ m¹⁷ rigidly secured thereto, the uppermost bracket m¹⁵ surrounding the guide-shaft O' and having a sliding fit thereon. In the two lower brackets m¹⁶ m¹⁷ is journaled a vertical shaft m¹⁸, having fast thereon a spur-gear m²⁰, and 55 in a swinging frame m²², pivoted between the brackets m¹⁶ m¹⁷, is journaled another vertical shaft m¹⁹, having fast thereon a spur-gear m²¹, caused to engage the gear m²⁰ by a spring m²³, secured to the plate m³⁰ and pressing against 60 said swinging frame (Figs. 8, 9 and 10). On the lower ends of the shafts m¹⁸ m¹⁹ are fast the fluted distributing-rolls m¹¹ m¹² which mesh into each other and pull the drawing L' through a trumpet m²⁴ of the usual construction, and deposit said drawing on the feed-aprons I when said shafts m¹⁸ m¹⁹ are rotated as hereinafter described.

The carriage M is prevented from swinging forward by a guide-wheel m³¹ which is fast on the shaft m¹⁸ and presses against the front 70 side of the vertical part o¹⁰ of the rail o². The shaft m¹⁸, has fast thereon at its upper end, a bevel-gear m²⁵, which engages a bevel-gear o¹⁶ which turns with the shaft o' and also has a longitudinal movement on said shaft with 75 the carriage M, said shaft having a key-seat o²⁹ extending from end to end thereof, engaged by a spline secured in the hub of said bevel-gear o¹⁶.

The shaft O' (Figs. 3 and 6) is rotated through 80 a train of gears, as follows: The gear o¹⁸, fast on the shaft m² of the sprocket-wheel m', and engaging the intermediate gear o¹⁹, the latter engaging the gear o²⁰, fast on the shaft o²¹, and a bevel-gear o²² on said shaft o²¹ engaging a 85 bevel-gear o²³, fast on said guide-shaft O'.

The shaft m² is rotated through connecting mechanism above described from the shaft of the lower rear feed-roll N⁴.

An arm o²⁴ (Figs. 5 and 7), capable of swinging 90 on the shaft o²¹, is held in the desired position by a bolt o²⁵ which passes through a slot o²⁶, curved concentrically with said shaft o²¹, said arm having also a straight slot o²⁷ radial to said shaft o²¹, in which slot the stud o²⁸, on which 95 said intermediate gear o¹⁹ turns, is adjustable in a well-known manner, so that either of the gears o¹⁸ o²⁰ may be changed for a gear of a greater or less number of teeth to vary the speed of the distributing-rolls, and the amount 100 of drawing deposited thereby on the feed-aprons, the speed of the distributing - rolls being regulated according to the speed of the delivery of the drawing L'.

In said Patent No. 18,888 are represented 105 two levers, sometimes called latches, around the free end of which alternately is laid the bight of the drawing L', at the end of the traverse, to prevent the last delivered course of the drawing being pulled out of place by the 110 tension of the drawing, each lever or latch being raised out of such engagement just before a new bight is formed. The rolls which in said Apperly feed, as heretofore used, most 115 nearly correspond in position to my distributing - rolls are not distributing - rolls or feed-rolls, being placed too far apart to exert any holding pressure upon the drawing and serving merely as guide-rolls or idle-rolls. The 120 unequal contraction of the different courses or parallel lines of the drawing on the feed-aprons causes the edges of the lap formed by 125 said lines of drawing to be uneven and the outer slivers formed from said lap to vary so greatly in weight and size in different parts 130 that these outer slivers, one at each side of the machine, are called waste slivers and are commonly returned to the first breaker after passing between the rub-rolls, the rovings formed from the waste slivers being too uneven to be spun. These latches I am enabled 130 to dispense with, partly because I use the positively driven distributing-rolls m¹¹ m¹² which deliver the drawing uniformly at all

times when the carriage M is traversing in either direction, and partly because I lengthen the side-belts K, causing them to extend forward under the guide-frame O, as near as possible without interference, to the plane in which the rear faces of the distributing-rolls lie, so that the last-laid course of drawing will be caught between said side-belts and the feed-aprons before a new course is laid.

10 It will be understood that these side-belts K are parallel endless belts of card-clothing running on idle pulleys k and on other pulleys k' fast on the shaft k², the latter being provided with a fast gear k⁴ which engages a fast gear (not shown) on the shaft of the rear roll i' of the feed-aprons I, in the usual manner.

Heretofore it has been customary to use a single pair of card-clothed feed-rolls N' N² to take the lap of drawing from the feed-aprons 20 I and side-belts K (see Figs. 2 and 11), and deliver the same to leaders-in (not shown) or directly to the tumbler C, which in turn delivers the fibers to the main cylinder B. I arrange a second pair of feed-rolls N³ N⁴, between said first pair and the tumbler, the center of the roll N⁴ or lower roll of the second pair being at equal distances from the centers of the roll N' N² said second pair being precisely like the first pair, but run at a 25 higher rate of speed in order to draw the fibers and present them to the tumbler at right angles to the axis thereof, instead of parallel therewith, in order that the fibers may be placed straight on the cylinder B and to prevent the outer slivers from a variation in 30 weight and size due to the irregular bending of the drawing L' at the sides of the lap. The upper front feed-roll N' has a gear n' which engages a precisely similar gear (not shown) 35 on the shaft of the lower front feed-roll N², in the usual manner, so that said front feed-rolls are driven at the same surface speed.

The shaft of the lower front feed-roll N² is provided with a spur gear n which engages a 40 spur-pinion n², secured to a bevel gear n³ concentrically therewith, said bevel gear n³ engaging a bevel pinion n⁵, fast on the front end of the side shaft n⁶, said side shaft having on its rear end another bevel gear n⁷ which 45 engages a bevel-pinion n⁸, fast on the shaft e of the lower doffer-roll E', said lower doffer-roll being driven through a belt and gearing from the shaft B' of the main cylinder B.

The shaft of the upper rear feed-roll N³ is 50 provided with a spur-gear n⁴ which engages a precisely similar gear n⁹ on the shaft of the lower rear feed-roll, so that both rear feed-rolls have the same rate of speed (see Figs. 2, 11 and 12) and the shaft of the lower rear 55 feed-roll is provided with a band-pully n¹⁰ (Fig. 1) connected by a belt n¹¹ with a pulley b fast on the shaft of the main cylinder. The roll N⁴ takes the fiber from the rolls N' N² and carries it up to the roll N³ which also 60 cleans the fiber from the roll N'.

The fibers are presented by the rear feed-

rolls to the tumbler C which runs at a greater rate of speed than said rear feed roll which delivers the fibers to the main cylinder B, as above stated, in the usual manner. In the 70 angle below and between said tumbler and main cylinder I arrange a lumper-roll P, the same being covered with a card clothing and rotating in the direction shown by the adjacent arrow in Fig. 11, being driven by a belt 75 p' which connects the band-pulley p fast on the shaft of said lumper-roll with another band-pulley p², fast on the shaft e of the lower doffer-roll E'.

The lumper-roll does not entirely strip the 80 tumbler C but evens the stock on said tumbler, catching the bunches and surplus stock on said tumbler and pulling the bunches apart, the adjacent surfaces of said tumbler and lumper revolving in opposite directions. 85 The lumper-roll is stripped by the cylinder B.

I claim as my invention—

1. The combination of the carriage-body, a frame, movable thereon, the horizontal supporting-shaft, a bevel-gear supported on said shaft and rotary therewith and movable longitudinally thereon with said carriage-body, two parallel shafts one of which is journaled in said carriage-body and the other of which is journaled in said frame, each of said parallel shafts being provided with a fluted distributing-roll, said rolls engaging each other, and a spring, arranged to force said frame toward said carriage-body, to keep said distributing rolls in engagement with each other, 95 the parallel shaft journaled in said carriage-body having a bevel-gear fast on said last named shaft and engaging said first named bevel-gear, as and for the purpose specified.

2. The combination of the carriage-body, 100 a swinging frame pivoted thereto, the horizontal supporting-shaft, a bevel gear supported on said shaft and rotary therewith, and movable longitudinally thereon with said carriage-body, two parallel shafts, one of which is 105 journaled in said carriage-body and the other of which is journaled in said swinging-frame, each of said parallel shafts being provided with a fluted distributing-roll,—said rolls engaging each other—and a spring secured to 110 said carriage-body and operating upon said swinging-frame to keep said distributing-rolls in engagement with each other, the parallel shaft journaled in said carriage-body having a bevel-gear, fast on said shaft and engaging 115 the bevel-gear first above-named, as and for the purpose specified.

3. The combination of carriage-body, a swinging-frame pivoted thereto, the horizontal supporting-shaft, a bevel gear supported 120 on said shaft and rotary therewith and movable longitudinally thereon with said carriage-body, two parallel shafts, one of which is journaled in said carriage-body and the other of which is journaled in said swinging-frame, each of said parallel shafts being provided with a fluted distributing-roll and with 130

a spur-gear which engages the spur-gear of
the other parallel shaft, and a spring to keep
said spur-gears in engagement with each
other, the parallel shaft journaled in said
5 carriage-body, having a bevel-gear fast
thereon and engaging said first named gear,
as and for the purpose specified.

In witness whereof I have signed this speci-
fication, in the presence of two attesting wit-
nesses, this 7th day of February, A.D. 1892.

EDDO V. BATES.

Witnesses:
